ATTORNEY

UNITED STATES PATENT OFFICE

RALPH WATSON, OF PHILADELPHIA, PENNSYLVANIA

LOOSE-LEAF BINDER

Application filed January 25, 1930. Serial No. 423,322.

My invention relates to loose leaf binders and is particularly adaptable to those loose leaf binders which may be used for binding check books, account books and the like, wherein it is desirable to have the pages lie flat during the insertion of the necessary written data thereon.

One object of my invention is to provide a loose leaf binder having certain features of structure, arrangement and assembly whereby the binder may be readily permanently attached to a pile or stack of leaves having punched or perforated edges and, once attached, cannot readily be detached therefrom, the leaves being permanently held in such a way that when the book is opened, the pages on both sides of the binder rings lie flat and the stack of leaves on one side of the binder rings or elements prevents the detachment of the rings from the support in which they are permanently mounted.

A further object of my invention is to provide a loose leaf binder which is particularly adapted for use in the binding of check books and the like, wherein the pile or stack of pages on the right-hand side of the binder will lie flat and convenient to write upon and the stubs on the other side of the binder rings or arches will also lie flat without any tendency whatever to fall forwardly and pile up on the pages on the right-hand side of the said rings or arches.

A further object of my invention is to provide a loose leaf binder of the character above described, in which the covers may be folded back on each other, back to back, with the leaves on one side of the binder rings and the stubs on the other side lying flat, so that the book will occupy a considerably smaller area when so folded and placed on a desk than such a book ordinarily requires on the desk for the entry of data therein.

A further object of my invention is to provide a convenient easy mode of assembling the binder with the leaves therein, whereby stiff, resilient separate binder rings or U-shaped arches may be easily sprung into recesses provided in the edges of a metallic backing strip, secured to the cover and, hav-

ing once been sprung therein, are firmly and permanently held in said notches by the resiliency of the arches themselves and by the cooperation of the leaves of the book mounted therewith.

A further object of my invention is to provide a loose leaf binder structure in which the elements comprise but three separate parts, one of which is adapted to be attached to a cover by two simple eyelets or rivets 55 passing therethrough.

Other objects of my invention will appear in the specification and claims below.

Referring to the drawings forming a part of this specification, in which the same reference characters are employed throughout the various views to designate the same parts,

Fig. 1 shows, in perspective, a cover with my improvements in loose leaf binders secured thereto, with the cover lying open and with the stack of pages or checks lying flat on the right-hand side of the rings or arches;

Fig. 2 is a plan view on a larger scale of the loose leaf binder elements, parts being broken away between the end of the strip, 75 and showing the upper ring or arch in its final or locked position and indicating the lower ring or arch in dot-and-dash lines in the position in which it is placed over the edges of the backing strip before it is turned 80 and sprung into its seat or notch on the right-hand side of the binder, and also showing the pages or leaves swung over to the left-hand side of the binding element to permit of the fastening of the rings or arches to the 85 backing strip;

Fig. 3 is a cross-sectional view on the line 3—3 of Fig. 2;

Fig. 4 is a fragmentary vertical sectional view of the metallic backing strip or support 90 taken on the line 4—4 of Fig. 2; and

Fig. 5 is a fragmentary view of the edge of the backing strip or support showing one of the embossed or raised portions and the notch therein provided.

The loose leaf unit embodying my invention and which is adapted to be secured to any suitable covering comprises but three pieces, namely, the backing strip or support 1 95 of metal and two like rings or U-shaped 100

arches 2-2 arranged to be secured to the backing strip 1 in the manner to be described. The strip 1 is provided on its left-hand edge with two substantially semi-circular struck-up portions 3-3' each of which is provided respectively with a small substantially semi-circular notch 4, preferably substantially concentric with the raised portions 3 or 3' in which the notch is made. The opposite edges of the backing strip or support 1 is provided with two struck-up or embossed portions 5-5', preferably elongated in a direction parallel to the length of the strip and each struck-up portion is provided with an irregular recess comprising a deep portion 6, a substantially semi-circular portion 7 and an inclined cam portion 8, extending from the bottom of the deep portion 6 and leading into the semi-circular portion 7, at a point well above the bottom thereof. The shallow portions 7-7 are respectively directly opposite the notches 4-4. The irregular recesses 6-6 are disposed complementally with respect to each other and symmetrically with respect to a line midway between the notches 4, 4 and normal to the length of the strip; that is to say, the deep portion 6 in the struck-up portion 5 is below its coacting shallower portion 7, while the deep portion 6, in the struck-up portion 5' is above its coacting shallow portion 7.

The rings 2, 2 are exactly alike and made of stiff resilient wire circular in transverse cross-section. Each comprises a curved portion 9, preferably substantially semi-circular, and two like short parallel ends or prongs 10, 10 provided near their ends with grooves forming necks 11, 11 of small diameter and thin disk-like heads or flanges 12, 12 at the extremities of the straight portions 11, 11 is substantially the same as the diameter of the notches 4, so that when the necks 11, 11 are seated therein they fit closely against the surfaces of said notches. The thickness of the heads or flanges 12, longitudinally of the straight portions 10, 10, is small and the struck-up or raised portions 3, 3' and 5, 5' are elevated above the surface of the strip 1 only sufficiently to permit the thin heads 12, 12 to slide therein. The distance between the center of a notch 4 and the center of the coacting deep notch 6 respectively is substantially equal to the distance between the axes of the straight portions 10, 10 of a ring or arch member 2. The distance between the center of a notch 4 and the center of the opposite shallow notch 7 is substantially greater than the distance between the axes of the said straight portions 10, 10 so that in assembling an arch or ring on the strip 1, one neck of a ring or arch 2 is first placed in a notch 4 on the left-hand side and the other neck 11 in the deep notch 6 on the opposite side of the strip as indi-

cated in dot-and-dash lines in Fig. 2. This is readily effected by slightly springing apart the arms or straight portions 10 of the rings or arches 2 to bring the heads or flanges 12, 12 below the under sides of the raised portions 3, 5 or 3', 5' respectively. After having been placed in the position, (as shown in dot-and-dash lines in Fig. 2), the ring or arch is swung clockwise around the axis of the neck 11 which is in the notch 4, and over the inclined camming section 8 spreading the prongs 10, 10 until the right-hand prong snaps into the shallow notch 7. In the upper half of Fig. 2 the ring 2 is shown as having been sprung into and being retained in the upper notch 7 after the right-hand prong 10 has been forced upwardly anti-clockwise from the deep notch 6 in the embossed portion 5 over the camming section 8. The distance between a pair of coacting notches 4 and 7 is greater than the distance between the notches 4 and 6 and slightly greater than the normal distance between the necks 11, 11 of a ring or arch 2 so that in traveling from the position shown for instance in Fig. 2 in the dot-and-dash lines over the camming section 8, the ends of the ring will be sprung apart slightly, and will be under a tension after the neck 11 on the right-hand side of the arch or ring has been sprung into its shallow seat 7.

It will now be clearly apparent that one ring or arch 2 (the upper one) will be swung about the axis of its left-hand prong in an anti-clockwise direction in being cammed into the upper shallow notch 7 and that the other ring (the lower one) will be swung in a clockwise direction in being cammed into the shallow notch 7, and that the disposition of one pair of notches 6, 7 is therefore complemental with respect to the other pair of notches 6, 7.

Each notch 7 has a low wall on the side adjacent the coacting cam surface 8 and a high wall on the opposite side and on its high side the notch is preferably deeper than the radius of the neck 11 to prevent the ring from being forced over said wall in turning the ring around the axis coincident with the center of a notch or recess 4.

Having thus described the structure and the manner in which the three parts of the binding element may be easily assembled without the use of screws, nuts or other fastening devices for locking the rings 2 and backing strip 1 together in firm permanent engagement, the manner in which this element is used will now be described.

The strip 1 is preferably provided with two holes 13, 13 through which pass rivets 14, 14 for securing the strip 1 to the back cover 15 of a binder which may be of any suitable construction but which is preferably composed of three parts, namely, the back cover 15, the back 16 and the front cover 17. The

strip 1 is preferably riveted to the back cover 15 so that its left-hand edge is adjacent and parallel to the flexible hinge portion 18 between the back cover 15 and the back 16, and the width of the back 16 is substantially equal to the height of the arches 2 so that when the book is closed the front cover 17 will lie flat on the stack of leaves lying on the inside of the back cover 15. The connection 19 between the front cover 17 and the back 16 is hinge-like and flexible, like the connection 18 between the back cover 15 and the back 16.

To secure a stack of pages or leaves 20 in a binder, a prong or straight portion 10 of an arch or ring 2 is inserted through the aligned holes 21 punched through the leaves 20, and the head 12 below the leaves is slid into struck-up portions 3 of the strip 1 to bring a neck 11 into a notch 4 as shown in Fig. 3. The other straight portion or prong 10 of the ring or arch, after having been placed in the deep notch 6 is then swung around the axis of the first arm (which is in the notch 4) as a center, over the cam portion 8 until the neck 11 snaps into the shallow notch 7. In a similar manner a like ring or arch 2 is inserted through the other series of perforations in the stack of pages 20 and the neck 11 of the prong is fitted into the notch 4 of the raised portion 3' and the other neck is fitted into the deep notch 6 of the raised portion 5' and is then swung downwardly around the center of the notch 4 as an axis into the lower shallow notch 7. It is to be observed that in attaching the leaves to the binder the second page of each leaf is uppermost and that the stack of leaves lies over and against the inside of the front cover. After the leaves have thus been fastened into the cover, the stack of leaves 20 may be swung over the curved portion 9 of the rings or arches 2 bringing the stack of leaves to rest on the inside of the back cover 15; that is to say, from the angular position shown in Figs. 2 and 3 to the transverse position shown in Fig. 1.

When the leaves are so secured to the loose leaf binder and are resting upon the back cover 15, as shown in Fig. 1, the stack of leaves 20 insures the retention of the ends of the rings or arches in the notches 7, 7 respectively, for if any force were imparted, for instance, to the upper ring or arch 2 tending to turn it clockwise around the arm or prong 10 in the notch 4 of the section 3 as an axis, then that force is transmitted through the stack of leaves 20 to the arm or prong 10 of the lower ring in the recess 7 of section 5' and against the high edge of the shallow notch 7 in said section over which the right-hand side of the lower ring 2 cannot be moved. Similarly, any motion in an anti-clockwise direction of the lower ring 2 about the notch 4 in the elevated section as a center

is resisted by the high shoulder on the upper side of the notch 7 in the elevated portion 5 transmitted thereto through the stack of leaves 20.

One of the features of this invention is that any pressure imparted tending to move one of the arms of the rings 1 holding leaves in the binder out of its notch 7 onto the cam surface 8 is resisted by the higher wall of the shallow notch 7 in which the other ring is seated. The leaves therefore are operative to prevent the rings or arches 2 from being loosened from their backing engagement with the notches 7. Thus are the leaves easily mounted in the binder forming the subject-matter of this invention; the rings or arches are easily slid over the sections 8 to impart tension to the resilient rings or arches sufficient to cause them to remain firmly seated in the shallow recesses 7, 7, and when the leaves are secured thereon and the binder is lying on the back cover 15 in the position in which it is normally placed in using the book, the stack of leaves transmits any pressure tending to unseat one ring or arch to the other ring and against the high side of the notch 7.

When the binder is used to hold checks in a check book, as shown in Fig. 1, the checks lie flat on the back cover 15 and to make the check book occupy less space when open on a desk or table, the front cover 17 may be swung about the flexible hinge portions 19 or 18 to a position flat against the outside of the back cover 15. When so folded the space required for the placing of the book flat on the desk or other support is only that of the area of the back cover 15 plus that of the stubs 23 on the left-hand side of the rings or arches 2.

Having thus described my invention, what I claim and desire to protect by Letters Patent of the United States is:

1. In a device of the character described, the combination with a cover comprising a back cover, a front cover and a back freely hingedly secured to said front and back covers, of a metal strip having parallel longitudinal edges rigidly secured to said back cover parallel and adjacent to said back and provided with a substantially semi-circular notch in one edge and an irregular recess in the opposite edge, said irregular recess having a substantially semi-circular portion directly opposite said notch, a deep portion on one side of said semi-circular portion and a cam edge extending from the bottom of said deep portion to a point a little above the bottom of said semi-circular portion, and a stiff, resilient arch circular in transverse cross-section, and the prongs of which are each provided with a circumferential groove forming a short neck near the end of each prong, the distance between the semi-circular notch on one edge and said deep portion

of said recess on the opposite edge being sufficient to permit the seating of the necks of the prongs therein without substantially springing the prongs apart and the distance between said notch and the semi-circular portion of said recess being substantially greater and sufficient to place the prongs under substantial tension, when the arch is rotated about the prong in the notch as an axis, and the neck of the prong and the recess is forced over said cam portion into said substantially semi-circular portion of said recess.

2. In a device of the character described, the combination with a cover comprising a back cover, a front cover and a back freely hingedly secured to said front and back covers, of a metal strip having parallel longitudinal edges rigidly secured to said back cover parallel and adjacent to said back and provided with a substantially semi-circular notch in one edge and an irregular recess in the opposite edge, said irregular recess having a substantially semi-circular portion directly opposite said notch, a deep portion on one side of said semi-circular portion and a cam edge extending from the bottom of said deep portion to a point a little above the bottom of said semi-circular portion, and a stiff, resilient arch circular in transverse cross-section, and the prongs of which are each provided with a circumferential groove forming a short neck near the end of each prong, the distance between the semi-circular notch on one edge and said deep portion of said recess on the opposite edge being sufficient to permit the seating of the necks of the prongs therein without substantially springing the prongs apart and the distance between said notch and the semi-circular portion of said recess being substantially greater and sufficient to place the prongs under substantial tension, when the arch is rotated about the prong in the notch as an axis, and the neck of the prong and the recess is forced over said cam portion into said substantially semi-circular portion of said recess, the portion of said strip surrounding said notch and recess being embossed upwardly to permit of the insertion of the end of said prong thereunder.

3. In a device of the character described, a cover, a parallel sided metal strip rigidly secured to the cover, a pair of stiff but resilient U-shaped arches circular in transverse cross-section, each prong of which is provided with a groove near the free end thereof to form a neck and a thin disk-like integral head on the end of each prong, said strip being provided with two spaced substantially semi-circular notches in one edge of a diameter substantially that of the prongs at said grooves and with two irregular recesses in the opposite edge, each recess comprising a substantially semi-circular portion directly opposite a notch in the opposite edge, a deep portion and an inclined cam portion extending from the bottom of said deep portion to a point well above the bottom thereof, said recesses being complementary with respect to each other and symmetrical with respect to a line normal to the length of said strip and midway between said recesses, the distance between a notch on one edge and the deep portion of the cooperating recess on the other edge being sufficient to permit the insertion of the prongs of an arch therein with said strip in said grooves, the distance between said notch and the semi-circular portion of said recess being greater, so that when one neck of an arch is in said notch and the other neck of said arch is in said recess and the said last-mentioned neck is slid up over said cam portion into said semi-circular portion, the prongs will be under tension holding said arches firmly seated in said notch and recess, the portion of said strip surrounding said notches and recesses being embossed upwardly for the lateral insertion of a head of an arch thereunder.

4. In a device of the character described, a cover, a parallel sided metal strip rigidly secured to the cover, a pair of stiff but resilient U-shaped arches circular in transverse cross-section, each prong of which is provided with a groove near the free end thereof to form a neck and a thin disk-like integral head on the end of each prong, said strip being provided with two spaced substantially semi-circular notches in one edge of a diameter substantially that of the prongs at said grooves and with two irregular recesses in the opposite edge, each recess comprising a substantially semi-circular portion directly opposite a notch in the opposite edge, a deep portion and an inclined cam portion extending from the bottom of said deep portion to a point well above the bottom thereof, said recesses being complementary with respect to each other and symmetrical with respect to a line normal to the length of said strip and midway between said recesses, the distance between a notch on one edge and the deep portion of the cooperating recess on the other edge being sufficient to permit the insertion of the prongs of an arch therein with said strip in said grooves, the distance between said notch and the semi-circular portion of said recess being greater, so that when one neck of an arch is in said notch and the other neck of said arch is in said recess and the said last-mentioned neck is slid up over said cam portion into said semi-circular portion, the prongs will be under tension holding said arches firmly seated in said notch and recess.

5. In a device of the character described, a cover, a parallel sided metal strip rigidly secured to the cover, a pair of stiff but resilient U-shaped arches circular in transverse cross-section, each prong of which is provided with a groove near the free end thereof to form a neck and a thin disk-like integral head on the end of each prong, said strip being provided with two spaced substantially semi-circular notches in one edge of a diameter substantially that of the prongs at said grooves and with two irregular recesses in the opposite edge, each recess comprising a substantially semi-circular portion directly opposite a notch in the opposite edge, a deep portion and an inclined cam portion extending from the bottom of said deep portion to a point well above the bottom thereof, said recesses being complementary with respect to each other and symmetrical with respect to a line normal to the length of said strip and midway between said recesses, the distance between a notch on one edge and the deep portion of the cooperating recess on the other edge being sufficient to permit the insertion of the prongs of an arch therein with said strip in said grooves, the distance between said notch and the semi-circular portion of said recess being greater, so that when one neck of an arch is in said notch and the other neck of said arch is in said recess and the said last-mentioned neck is slid up over said cam portion into said semi-circular portion, the prongs will be under tension holding said arches firmly seated in said notch and recess, the portion of said strip surrounding said notches and recesses being embossed upwardly for the lateral insertion of a head of an arch thereunder.

In witness whereof, I have hereunto set my hand this 24th day of January, 1930.

RALPH WATSON.
